UNITED STATES PATENT OFFICE.

JAMES F. McELROY, OF ALBANY, NEW YORK, ASSIGNOR TO CONSOLIDATED CAR HEATING COMPANY, A CORPORATION OF WEST VIRGINIA.

ELECTRICALLY-HEATED BOILER.

1,072,748.

Specification of Letters Patent.

Patented Sept. 9, 1913.

Application filed September 16, 1908. Serial No. 453,250.

To all whom it may concern:

Be it known that I, JAMES F. McELROY, a citizen of the United States, and a resident of the city of Albany, county of Albany, 5 State of New York, have invented certain new and useful Improvements in Electrically-Heated Boilers, of which the following is a full, clear, and complete disclosure.

The object of my invention is to provide 10 a boiler in which the generation of steam or vapor may be accomplished by the use of an electric current in an economical and efficient manner. Electrically heated boilers, such as form the subject-matter of my 15 invention, are particularly applicable to steam heating where it is desired to do away with the use of any primary means for the generation of heat, such as by the combustion of gas, coal or oil.

20 At the present time passenger cars employed on railroads are provided with means for heating, during cold weather, by steam taken from the locomotive. Passenger trains or cars are now not only operated 25 over considerable lengths of track where electric locomotives are employed solely, but such trains are also operated over tracks by the use of steam locomotives for a part of the distance, and by electric locomotives for 30 another part of the distance. When a train of cars, equipped with the usual steam heating apparatus and drawn by a steam locomotive, reaches certain points where it enters what is sometimes termed the "electric 35 zone," or that portion of the line where the electric locomotive is used, it is necessary to provide some means for heating the cars which were before heated by steam from the boiler of the steam locomotive.

40 One object of my invention is therefore to provide a steam boiler which may be carried by an electric locomotive, and within which steam may be generated by the same electric current through which the locomotive is operated. By the application of efficient mechanism for this purpose, the necessity of re-equipping the cars with electric heating apparatus is obviated. In the adaptation of my invention to the heating 45 of railway cars, I preferably provide a steam boiler that is mounted on a locomotive, the boiler being provided with heating apparatus through which the electric current flows, so that steam is generated in 50 the boiler, which boiler is connected to the

train pipes, so that the steam generated may be used in the ordinary manner. However, I do not wish to be understood as limiting myself to this particular application of my invention, for such electrically heated 60 boilers may be used under other conditions and in other situations, as the occasion may demand.

Further objects and features of my invention will be apparent from the following specification and the accompanying drawings forming a part thereof, in which—

Figure 1 is a longitudinal sectional view of a boiler showing the means for heating the boiler tubes; and Figs. 2, 3, 4, 5, 6, 7 70 and 8 are sectional views of the heating elements showing the manner of fixing and insulating the same in a boiler. Figs. 9 and 10 are respectively end and side views of the boiler tube shown in Fig. 8, also indicating the connector between two of the heating elements; Fig. 11 is a side elevation of a boiler showing the casing thereof in section and indicating a modification comprising means whereby air is made to circulate through the boiler tubes. 80

Referring to the drawings the numeral 1 indicates a boiler of my suitable or preferred construction to which my invention is applied, Fig. 1 of the drawings shows a section 85 of a boiler, one of the boiler tubes or flues 21 being shown in section and illustrating the heating element in the form of a tube 22 in position therein. These tubes are made of thin metal of the requisite thickness to give sufficient resistance to the passage of electric current to generate the amount of heat desired in each element. These tubes are preferably made of perforated metal as indicated at 90 23, although they may be made plain if desired and a low resistance only is required. The proportion between the diameter of the boiler tubes and that of the heating element is preferably 2 to 1. For instance, where the boiler tubes are $2\frac{1}{2}$ inches inside diameter, the outside diameter of the heating element is preferably $1\frac{1}{4}$ inches. I have shown these heating elements in the form of tubes, and it is to be understood that I may use other shapes according to the circumstances 100 of individual cases. I prefer to use iron as the material of which these tubes are made, such iron being pure and free from carbon. By the use of perforated metal I am able to use a metal of a given and uniform gage 110

or thickness, and I may vary the resistance of the heating element or tube by varying the number of the perforations or their form. While I have shown in the drawings tubes 5 perforated with round holes it should be understood that I have shown the same for illustration, and I may use for this purpose sheet metal having slotted perforations either running transversely or longitudinally 10 of the tubes, and I may arrange the perforations or slots in different ways, or I may stagger the same so that the electric current in passing along the tube may take a zigzag course at a much greater 15 length than if running longitudinally. The heating elements of tubes 23 being light may be supported within the boiler and within the boiler tubes by means of insulators 24 made of porcelain or other suitable material. 20 Although these insulators may be made of any desired form, they are preferably made with a wide, flat circumferential groove 25, in which a band 26 of crinkled or corrugated steel or other metal may be placed so as to 25 hold the insulators centered or concentric with the boiler tubes, and at the same time prevent rattling therein. This construction also allows the porcelain insulators to be adapted to a boiler tube of irregular dimensions, thereby preventing unusual strains 30 and liability of breaking where there is a variation in the diameter and cross-section of the boiler tubes.

Instead of the band of crinkled metal I 35 may wind the circumferential groove in the insulator with a cord of asbestos or other suitable material indicated at 27 that will withstand a high temperature and which will be elastic enough to cushion the insulator against the inside of the boiler tube. The insulators at the ends of the heating elements, where they pass into the boiler tubes, may be made in any desirable shape to firmly hold the heating elements in position. In Figs. 1 and 8 I have illustrated 40 two forms of end insulators as indicated by the numerals 28 and 29. The ring insulators 24 are shown as supporting the perforated tubes inside of the boiler tube at convenient 45 distances between the end insulators 28, and I prefer to place such ring insulators so as to have the tubes supported at points about two feet apart. The ring insulators are 50 preferably secured in position on the heating tube by raising small round hemispheres or 55 projections on the metal of the heating tube on each side of the ring as indicated at 30. These projections prevent the ring from sliding longitudinally on the heating element or 60 tubes. As indicated in Figs. 4, 7 and 8, the ring insulators may be made in two semicircular parts 31, each exactly alike, and being provided with tongues and corresponding 65 grooves 32 at their respective ends, so that each part of the insulator will fit its corre-

sponding part so that the tongues and grooves will prevent the halves of the insulator from moving transversely in relation to each other. In this form of insulator, when asbestos cord is used, the ends of the cord project through holes indicated at 70 33, and are secured by tying knots in the cord. This form of divided insulator enables me to place the same in position around a heating element when the hemispherical 75 projections are used. As the cord binds the two parts of the insulator together, they may be placed in position upon the heating element and then the heating element pushed through the boiler tube to the requisite 80 point. The end porcelain insulators, such as indicated at 28 and 29, preferably have shoulders indicated at 34 and 35, which rest against the ends of the boiler tubes or against the heads of the boiler. The grooves in the 85 end porcelain insulators are preferably located some distance inward from the end of the boiler tube, because these insulators are protected from touching the boiler tube by the crinkled metal bands or by the asbestos cord in the circumferential groove. I thus prevent the insulator from being forced out of the boiler by any expansion of the heating element or tube, owing to the heat generated. Sufficient space is allowed at the 90 end of the tubes and between the outer cover or door 8 to allow expansion that may take place in the heating tubes, and I preferably further protect the door 8 by means of insulation on its inner surface, as indicated 95 at 36.

The heating elements within the boiler tubes may be connected in series or in parallel, or partly in series and partly in parallel, according to the voltage, amount of resistance, and the amount of heat desired. The connectors which I employ for this purpose may be of any preferred form, but in Fig. 1 I have illustrated one form of such connectors which I deem preferable. These 10 connectors 37 are made of a bar of metal of sufficient length to extend from the end of one tube across to the end of the adjacent tubes, and is provided with holes corresponding to the relative positions of the 11 ends of the heating elements or tubes that are to be connected. The ends of the heating tubes are inserted through the holes in the connecting bars 37 as indicated at 38, and the heating tube is then expanded in the 12 holes. For this purpose I preferably use a ferrule 39 made of the same metal as the connecting bars, and this is forced by pressure into the heating tube, thereby expanding and holding the heating tube in close 13 and continuous contact with the eye or ring in the connecting bar 37. The connecting bars, the ferrule and the heating tubes are all preferably made of the same metal, so that the same degree of expansion is pro- 14

duced by any change of temperature of the tubes and the surrounding air. Otherwise the contacts might become loose by the unequal expansion and consequent creeping of the parts upon each other, which would tend to loosen the contacts between the tubes and the connectors.

In Figs. 8, 9 and 10, I have shown a modification of the devices for locating the ends 10 of the heater elements in the ends of the boiler tubes. This comprises a ring 40 having lugs 41 adapted to contact with the interior of the boiler tubes and an interior flange 42 adapted to be seated in the groove 15 in the insulator 29. This form of supporting the insulator and the ends of the heater element provides free space outside of the insulator 29 so that air may pass therethrough in addition to the passage of air 20 through the end of the heater element and permits a more complete circulation. This manner of supporting the end of the heater element is particularly adapted to the modification of the invention shown in Fig. 11. 25 In this form of boiler the heater elements are located in one set or portion of the tubes only, such as the tubes indicated at 44, the upper set of tubes 45 being plain and without heater elements contained therein. The 30 ends of the boiler are provided with covers or casing 46 and 47, forming spaces through which the air may leave one set of tubes and enter the other set of tubes. A small dividing strip or partition 48 is provided within 35 the casing 46, and in the lower space thus formed with the casing 46 is located a fan 49, driven by a suitable motor 50. The object of the motor and fan is to force circulation of air through all the tubes. In this 40 way, the heated air is forced through the tubes in front of the fan and at the opposite end of the boiler beneath the casing 47 passes into the upper set of tubes and again into the space beneath the casing 46, where 45 it is further acted upon by the fan. This arrangement causes the air to move more quickly over the heated surfaces of the heater elements and distributes the heat evenly throughout the boiler. Inasmuch as 50 this circulation of the air greatly increases the convection of the heat from the heating elements to the boiler tubes, the heat passes much more quickly from the heating elements to the boiler tubes and the efficiency 55 of the boiler is greatly increased. This construction also keeps the heating elements much cooler than they would be in a case where ordinary circulation is depended upon. It is obvious that I do not necessarily 60 need to locate the heating elements in this form of the invention in the tubes 44, for they may be inclosed in a similar manner, as the air is now forced into the boiler tubes 45, the heating of the air taking place 65 in the boiler tubes 44 and the air giving up

some of its heat in the boiler tubes 45, though in the present instance heat is also delivered to the water in the boiler through the tubes 44.

Having described this embodiment of my invention, which I at present deem preferable, I do not wish to be limited to the exact details and arrangement of parts herein set forth, for various changes may be made by persons skilled in the art without departing 75 from the spirit and scope of my invention.

What I desire to protect by Letters Patent of the United States is:

1. In an electrically heated boiler the combination with an air flue of a tubular metallic heating element therein extending through the flue and included in an electric circuit. 80

2. In an electrically heated boiler the combination with a plurality of air flues open at both ends to permit convection currents of air, of an air chamber at one end into which said flues open and heating elements in its several flues separated by an air space from the walls of the flue. 85

3. In an electrically heated boiler the combination with an air flue open at both ends to permit longitudinal convection currents of air of a metallic electrical heating element in the flue insulated from the interior wall thereof and included in an electric circuit. 90

4. In an electrically heated boiler the combination with an air flue open at both ends to permit convection currents of air of a tubular metallic heating element therein included in an electric circuit. 100

5. In an electrically heated boiler the combination with an air flue, of a tubular electric heating element therein open to permit internal convection currents of air within the element and separated by an air space from the interior wall of the flue. 105

6. In an electrically heated boiler, the combination with a liquid receptacle, of air flues open at both ends to permit convection currents of air and tubular heating elements in the several flues open to permit convection air currents in the interior of the tubular elements. 110

7. In an electrically heated boiler, the combination with a liquid receptacle, of air flues therein open at both ends to permit convection currents of air, and tubular heating elements open to permit internal air currents and separated by an air space from the walls of the flues to permit air currents between said heating elements and the walls of the flues. 120

8. In an electrically heated boiler, the combination, with a liquid receptacle, of tubes passing therethrough, electric heating devices within said tubes and extending beyond the ends thereof, covers forming spaces at the ends of said receptacle, and connect- 125

130

ors for connecting said heating elements electrically located in said end space.

9. In an electrically heated boiler the combination with a flue of a tubular heating element extending therethrough and open at its ends, the wall of said heating element being provided with openings to permit heated air to pass into said flue.

10. In an electrically heated boiler the combination with a flue of a tubular heating element extending therethrough and open at its ends, the wall of said heating element being provided with openings to permit heated air to pass into said flue, and 15 spaced insulators for supporting said heating element within said flue.

11. In an electrically heated boiler the combination with a flue of a tubular heating element extending therethrough and 20 open at its ends, the wall of said heating element being provided with openings to permit heated air to pass into said flue, insulators for supporting said heating element, and means for cushioning said insulators.

12. In an electrically heated boiler, tubes passing therethrough, electric heating elements in said tubes, annular insulators between said tubes and heating elements for 30 maintaining the same relatively concentric, and cushions located between said insulators and their adjacent parts.

13. In an electrically heated boiler the combination with flues passing therethrough, 35 electric heating elements within said tubes,

insulators for supporting said heating elements within said flues and provided with peripheral grooves, and cushioning means engaging said grooves.

14. In an electrically heated boiler the combination with flues passing therethrough, 40 electric heating elements within said tubes, insulators for supporting said heating elements within said flues, said insulators being each formed of two members, and cushioning members for preventing separation of said insulator members.

15. In an electrically heated boiler, the combination, with a liquid receptacle, of pipes passing therethrough, an electric heating device separated from said receptacle by an air space, and means for producing air circulation between said heating devices and said tubes.

16. In an electrically heated boiler, the combination, with a liquid receptacle, of 55 tubes passing therethrough, heating devices contained in a portion of said tubes, air spaces at the ends of said tubes external to said receptacle, and means in one of said 60 air spaces for producing air circulation between said heating devices and the walls of said tubes.

Signed at Albany, in the county of Albany, this 10th day of September, 1908.

JAMES F. McELROY.
